UNITED STATES PATENT OFFICE.

ADAM WINGARD, OF SAN FRANCISCO, CALIFORNIA.

DRY-ORE PULVERIZER AND CONCENTRATOR.

SPECIFICATION forming part of Letters Patent No. 289,791, dated December 4, 1883.

Application filed September 16, 1882. (No model.)

To all whom it may concern:

Be it known that I, ADAM WINGARD, of the city and county of San Francisco, in the State of California, have made and invented 5 certain new and useful Improvements in Dry-Ore Pulverizers and Concentrators; and I do hereby declare that the following is a full, clear, and exact description of the same, reference being had to the accompanying drawings.

My invention relates to improvements in machines for treating ores in a dry state or without water, to disintegrate the particles and separate the mineral from dirt and other 15 worthless matter. It has for its object to provide a machine which has the capacity to work upon metalliferous earth in a dry condition, and is thereby adapted for use in localities where the supply of water is scarce or cannot 20 be had. This object I attain by constructing a machine for operation according to the following description, in which reference is made to the accompanying drawings by letters.

Figure 1 is an elevation in vertical longitudinal section of a machine constructed in accordance with my invention. Fig. 2 is an end elevation taken from the rear of Fig. 1, and is partly in vertical section. Fig. 3 is a longitudinal section of the table. Fig. 4 is a 30 view taken from the rear end thereof, and Fig. 5 is a detail view of the striker.

A is an open conical barrel, having longitudinal slits or openings formed by securing together a number of narrow staves or bars, 35 $a' a'$. It is fixed upon a horizontal shaft, w , from which it receives rotation, and is surrounded by a stationary case which incloses it from end to end, the case being open at the larger end. The matter to be treated is fed in 40 at one end, and, by a rapid rotation given to the barrel and the tumbling and falling of the material, pulverization of the lumps and particles results from the centrifugal action, and all matter fine enough to pass through the 45 openings is thrown out into the surrounding stationary chamber. A spiral flange, d' , fixed to the outside surface of the revolving barrel, runs in close proximity to the bottom of the stationary chamber and moves the pulverized 50 matter outward to the discharge end of this chamber. At this point of discharge a quick-silver-pocket, E, is formed by enlarging or carrying out the lower portion of the larger

end of the stationary chamber, just inside of the rim or flange j . This structure is combined with and operates in relation to a vibrating concentrating-table and an elevator-cylinder for acting upon all the matter that may not receive proper amalgamation in passing from the end of the stationary chamber. 60

F is a conical drum or chamber, somewhat larger at its smaller end than the outer end of the stationary chamber, so as to overlap the rim j of the last-named chamber, and has a number of pockets, $g g$, by which the matter 65 discharged into the chamber is raised and dropped through the center and upon a suspended shaking table, P. For this purpose the drum F has a rotary motion imparted to it, but the motion is less rapid than the motion of the pulverizing-barrel. The matter discharged from the pockets g receives the concentrating action of the shaking table, and the refuse matter therefrom falls upon the lower end of an inclined grating or grizzly, J, 75 whence it is carried out of the machine. All matter not capable of being reduced in the revolving barrel is discharged upon the upper end of this grizzly, and is conducted out of the drum without mixing with the pulverized 80 matter thrown out from the stationary chamber.

The general construction of this machine is as follows: Within a suitable frame-work, $y z$, I mount a horizontal shaft, w , in bearings 85 $w' w'$, and upon it, at one end, I fix the tapering barrel A. This barrel is constructed of a number of rectangular bars with tapering sides, which are laid and secured at regular distances apart, and in close order upon and 90 around two circular open heads, $d d$. Such construction gives a barrel with longitudinal openings a' between the staves all around. The chamber D is formed of a surrounding shell or case supported on uprights $z z$, and 95 projecting beyond each end of the barrel, so as to afford at the front a closed chamber, i , and at the rear a rim or flange, j , to fit into the end of a conical drum forming the elevator-chamber. Around the outside of the barrel 100 a spiral flange, d' , is bolted in a position to run close to the inside of the stationary chamber, and engage with and move forward the matter thrown into this space from the interior of the barrel. From a central opening 105 at the closed end of this chamber a flaring

sleeve, K, extends to and surrounds the front end of the barrel, and into it is carried the end of a chute or hopper, L, through which ore is fed into the barrel. The rear end of this chamber is provided with a pocket, E, which is formed on the lower half-circumference of the chamber, so as to extend below the level of its bottom.

F is the revolving elevator-cylinder, which is supported on friction-rollers N, and is driven by means of a gear-ring bolted on the circumference thereof, at its rear end, and a pinion, u, on the driving-shaft. This driving-shaft w' is mounted in boxes p p, upon the top of the frame and gives motion to the shaft w; also through the medium of the pulley F' F' and belt I. The rotary motion of the elevator-chamber is employed to raise the pulverized stuff discharged by the worm d' from the stationary chamber and throw it upon the table, and, therefore this motion is much less rapid than the rate of speed of the pulverizing-barrel.

g g are the elevator pockets or receptacles for lifting and dropping the material. Their construction and arrangement are shown in Figs. 1 and 2.

P is the shaking table for concentrating the mineral particles contained in the material discharged into the elevating-chamber. It has a peculiar rocking motion produced by raising its front and rear ends alternately, and also a trembling or shaking movement from the action of strikers R, which are operated under its bottom. The cams P', for rocking the table, are carried on a short shaft, T, held in bearings t* at each end—one in the frame and the other in a stationary hanger, T*—bolted to the upper part of the case and driven from the main shaft by means of the gear and pinion s s. The beaters or strikers R are simple levers having their outer arms shorter and lighter than the others, and provided with curved projecting ends against which the front and rear ends of the table are caused to strike in their alternate downward movements, thus throwing up the longer and heavier ends of the levers against the bottom of the table-surface. The shaft T is utilized as a means for directing several jets of air into the lower part of the revolving barrel and across the surface of the quicksilver-receptacle, for the purpose of preventing the accumulation of matter and the consequent clogging at such point. It is therefore made hollow, and is provided with several perforations, u' u', at the inner end, while the outer end is adapted to receive the end of an air-supply tube, v. The concentrating-table has an inclination to the rear, and is made of a piece of animal-hide with the hair laid uppermost. The trembling and rocking motions which are imparted to the table P cause the heavier particles to settle upon it, while the lighter and less valuable are thrown off. The hairy side of the skin aids in this, as it presents a rough surface to hold the heavy particles when once they are settled.

As thus constructed the operation of the machine is as follows: The material is fed into the barrel at the smaller end, and power 70 being applied to the shaft w, the contents of the barrel receives pulverization, and is discharged through the slits into the outer chamber, whence it passes over and in contact with the quicksilver in the receptacle. From the 75 rear end of the chamber it is then discharged into the revolving elevator-chamber, where, being caught by the buckets, it is raised up and dropped down upon the shaking table, where the mineral particles that have escaped 80 amalgamation are extracted from the refuse by settling and remaining on the table P, while the lighter and less valuable matter is carried or thrown off.

The lumps and other particles that are not 85 sufficiently reduced to pass through the barrel are discharged from the machine over the grizzly J.

Having thus fully described my invention, what I claim, and desire to secure by Letters 90 Patent, is—

1. The combination of the pulverizing-barrel A, the stationary inclosing-case D, the feed-hopper L, and the revolving elevator-chamber F, substantially as described. 95

2. The combination, with the pulverizing-barrel A, formed of staves or rods a' a', with spaces between them, and having the spiral flange d', of the outer stationary case having the feed-hopper and the pocket E, substantially as described. 100

3. The combination, with the pulverizing-barrel A and the stationary case D, having the feed-hopper L, of the elevator-chamber F, having the pockets, and means for rotating the 105 barrel and elevator-chamber at different rates of speed, substantially as described.

4. The combination, with the elevator-chamber F, having pockets g and means for rotating it, of the concentrating-table P, suspended 110 in central position within chamber-space, and means for rocking or shaking said table, substantially as described.

5. The combination, with the conical pulverizing-barrel A, of means for giving it a 115 rotary motion, means for feeding the material into it at the smaller end, the inclosing-case to receive the matter discharged through the aperture by the rotation of the barrel, and the inclined grating J, for receiving the matter 120 passing out from the interior of the barrel, substantially as described.

6. The combination, with the elevator-cylinder F, having rotary motion, as described, of the table P, its supporting-shaft T, provided 125 with cams and connecting-rods, for imparting a shaking motion, and the beaters R, applied beneath the table, to operate substantially as set forth.

Witness my hand and seal.

ADAM WINGARD. [L. S.]
